UNITED STATES PATENT OFFICE.

ROLAND PEARS AND WALTER SEFTON SUFFERN, OF BELFAST, IRELAND.

TWISTING FRAME.

Application filed November 24, 1924. Serial No. 751,853.

This invention relates to machines for twisting threads and yarns wherein the yarns are delivered to each individual spindle by a pressing roller that is normally maintained in contact with a driving roller and is driven by the latter through frictional contact. The invention consists in providing an improved arrangement of detector controlled mechanism for automatically disconnecting the pressing roller from the driving roller in the event of the yarn breaking or running out and an improved construction of clutches for simultaneously stopping the spindle and flyer.

According to this invention each pressing roller is mounted on a pivoted frame and is normally maintained in gear with the driving roller by a weighted arm. Each detector is slidably mounted in a weighted catch lever that is adapted to hold a weighted clutch lever in a position to maintain a clutch member appertaining to a spindle or flyer in its driving position, failure of the yarn releasing a detector which is then actuated by a tappet to disengage the catch lever from the weighted clutch lever whereupon the latter turns and disengages the clutch appertaining to the spindle and flyer and simultaneously lifts the weighted arm to disengage the pressing roller from the driving roller. Two hand operated control levers are provided, one for disengaging the pressing roller and stopping the spindles, and the other for engaging the pressing roller and starting the spindles.

A feature of the invention consists in providing means whereby the driven clutch member is caused to rotate at or about the speed of the driving clutch member before its teeth are brought into gear with the teeth of the driving clutch member with the result that shock or vibration between the teeth is eliminated.

In the accompanying drawings:—

Fig. 1 is a side elevation of part of a twisting frame constructed in accordance with this invention, and

Fig. 2 is a similar view of the lower part of the machine.

A indicates the yarn, B one of the spindles, C the pressing roller, D the driving roller, and E the detector.

Each pressing roller C is mounted on a pivoted arm c and is normally maintained in gear with the driving roller D by a weight c¹ or its equivalent on another arm c².

Each detector E is slidably mounted in a weighted catch lever e that is adapted to hold a weighted clutch lever e¹ in a position to maintain a clutch member appertaining to a spindle B or to the flyer F in its driving position. For this purpose a crank arm b is connected by a rod b¹ with an arm b² that engages an annular recess in an outer clutch member b³. This clutch member is slidably mounted on an inner clutch member b⁴ and is toothed at its lower end to engage teeth on a clutch member b⁵ that is rotatably mounted on the spindle B and is positively driven by gearing b⁶. The driving clutch member b⁵ is formed with a conical recess b⁷ to receive a conical end b⁸ on the inner clutch member b⁴. The latter is slidably mounted on the spindle B and is pressed towards the driving clutch member b⁵ by a spring b⁹ which encircles a portion of the spindle within the inner clutch member and exerts pressure against the latter and a clutch collar b¹⁰ that is rigidly fixed on the spindle. This clutch collar is formed with one or more recesses b¹¹ to receive one or more prongs b¹² on the inner clutch member. The upper end of the outer clutch member b³ is formed with one or more prongs b¹³ to engage one or more recesses b¹⁴ in a flange which extends around the inner clutch member b⁴. When a detector E falls through breakage or failure of the yarn it is actuated by a tappet e² to disengage the catch lever e from the weighted clutch lever e¹ whereupon the latter turns and lifts the clutch teeth on the outer clutch member and the conical surface on the inner clutch member out of gear with the corresponding parts of the driving clutch member b⁵. As the clutch lever e¹ turns, a portion e³ of it strikes a projection e⁴ on the weighted arm appertaining to the pressing roller C and moves the latter out of contact with the driving roller D. To restart the spindle the front end or handle e⁵ of the weighted clutch lever is depressed thereby causing a curved surface e⁶ on such lever to travel past a projection e⁷ on the catch lever e until such projection reengages a catch e⁸ on the clutch lever. When the latter is depressed in the manner described, the weight e¹ appertaining to the pressing roller returns the latter into gear with the driving roller D.

When the operating lever b² is lowered the spring b⁹ first moves the conical surface b⁷ of the inner clutch mem-

ber into gear with the conical recess b^6 in the driving clutch member, with the result that the spindle and the outer clutch member are caused to rotate at or about the speed of the driving clutch member b^5 . Further movement of the operating lever in the same direction then brings the teeth on the outer clutch member into gear with the teeth on the driving clutch member and as these two parts are prior to this operation rotating at or about the same speed the clutch is brought into gear without shock, noise, or vibration, and a positive drive is then imparted to the spindle. To stop the spindle by hand a handle such as c^4 may be provided on the arm c which carries the pressing roller C . When the attendant pulls such handle in a direction to disengage the pressing roller from the driving roller the weighted arm c^2 is raised until a portion c^5 of it engages an abutment c^8 on the weighted catch lever e and turns the latter to disengage the projection e^6 thereon from the catch e^7 on the weighted clutch lever whereupon the latter falls and disengages the spindle clutch and also retains the pressing roller in its disengaged position.

What we claim as our invention and desire to secure by Letters Patent in the United States is:—

1. In a machine for twisting threads and yarns the combination of a driving roller, a pressing roller; a pivoted frame carrying the latter, a weighted arm rigidly connected with the frame, a weighted catch lever, a

detector slidably mounted in the catch lever and maintained in an inoperative position by the yarn, a tappet for engaging the detector when the yarn fails, a weighted clutch lever adapted to engage the catch lever and the weighted arm, a clutch driven spindle provided with a sliding clutch member and an operative connection between the weighted clutch lever and the sliding clutch member. 40 45

2. In a machine for twisting threads and yarns, the combination of a driving roller, a pressing roller, a weighted arm rigidly connected with the frame, a weighted catch lever, a detector slidably mounted in the catch lever and maintained in an inoperative position by the yarn, a tappet for engaging the detector when the yarn fails, a weighted clutch lever adapted to engage the catch lever and the weighted arm, a clutch driven spindle provided with a sliding clutch member, an operative connection between the weighted clutch lever and the sliding clutch member, a hand operated control lever for disengaging the pressing roller from the driving roller and the sliding clutch member from the spindle driving clutch member and a hand operated control lever for engaging the pressing roller with the driving roller and the sliding clutch member with the spindle driving clutch member. 50 55 60 65

In testimony whereof we affix our signatures.

ROLAND PEARS.

WALTER SEFTON SUFFERN.
